UNITED STATES PATENT OFFICE.

ADOLPH RAIMUND BAUMANN, OF NEW YORK, N. Y.

CIGARETTE HOLDER AND EJECTOR.

Application filed September 19, 1927. Serial No. 220,496.

This invention relates generally to cigarette holders, and in particular to an improved cigarette holder and ejector provided for the purpose of holding a cigarette 5 in a mouth-piece during the smoking of the cigarette, and embodying a means of readily ejecting the burnt cigarette or the cigarette stub from the holder without necessitating the touching of the cigarette stub. 10 The object of the invention is to provide a cigarette holder and ejector of novel construction and arrangement of parts herein-after more fully described, claimed and illustrated in the accompanying drawing. 15 Fig. 1 illustrates my improved cigarette holder and ejector as same would appear when in use.

Fig. 2 is an enlarged longitudinal central sectional view thereof.

20 Fig. 3 is a perspective detail view of the ejector as embodied in my improved device.

Fig. 4 is a fragmentary longitudinal central sectional view illustrating a further development of my improved device showing 25 same in an engaged or "in use" position.

Fig. 5 is a similar sectional view to that shown in Fig. 4 showing same in a disengaged position.

Fig. 6 is a perspective detail view of a 30 cigarette holder proper used in the invention.

Fig. 7 is a fragmentary perspective detail view of an ejector used in this invention.

35 As here embodied my improved cigarette holder and ejector comprises a body member 10 of cylindrical construction, having formed therein at one extremity thereof, an axial opening 11 of suitable size, or diameter to permit one end of a cigarette 12 to be inserted therein so as to frictionally hold the cigarette 12 in an extended position as clearly shown in Fig. 1.

The opposite extremity of the body member 40 10 has formed therein an axial opening 13 extending in proximity to the above mentioned opening 11. The axial opening 14 formed in the body member 10 is of somewhat smaller diameter than the above mentioned 45 openings 11 and 13 and is intercommunicative with the said openings 11 and 13.

The ejector 15 is of tubular construction, 50 adapted to slidably engage in the opening 14 formed in the body member 10 and is provided with an enlarged extremity 16 or head, adapted to slidably engage in the

opening 11 formed in the body member 10. The ejector 15 is provided with a threaded portion 17 or extremity, as a means of securing same to the stem 18 which has formed 55 therein a threaded axial opening adapted to receive the threaded portion 17 of the ejector 15. The stem 18 is of cylindrical construction having formed therein an axial opening 19 extending longitudinally thereof 60 from one end thereof, intercommunicative with the above mentioned threaded axial opening adapted to receive the threaded portion 17 of the ejector 15. The stem 18 is provided with an enlarged extremity 20 as a 65 means of providing the usual mouth piece. The stem 18 is adapted to slidably engage in the opening 13 formed in the body member 10. The expansion spring 21 is positioned 70 in the opening 13 and is of coil construction 75 of suitable size or diameter to freely engage over the ejector 15. The enlarged head 16 of the ejector 15 has formed therein a transverse or radial slot 22 adapted to receive a screw driver blade, or the like, as a means of 80 threadedly securing the said ejector to the stem 18.

The above described construction is such as will permit the cigarette 12 when smoked or the stub of the said cigarette to be readily removed or ejected therefrom by forcing the stem 18 inwardly as is obvious from the foregoing description. The stem 18 may be held in the mouth of the smoker, gripped between the teeth and the body member 10 85 forced inwardly, as a means of ejecting the cigarette stub.

In Figs. 4, 5, 6 and 7 of the accompanying drawing, I have shown the body member 10 having formed therein, at one extremity 90 thereof, an axial opening 23, somewhat tapered inwardly, from the said extremity thereof. The cigarette holder proper 24 is of frustum conical construction having a tapered axial opening 25 formed therein, 100 and is slotted longitudinally, as at 26, and has formed therein a plurality of elongated slots 27, extending from the smaller extremity or end thereof, in proximity to the opposite end thereof. The cigarette 105 holder proper 24 is constructed of comparatively thin material, preferably spring brass, spring steel, or the like, and is adapted to frictionally engage in the above mentioned opening 23 formed in the body member 10. The snap ring 28 is of similar material to 110 the cigarette holder proper 24 and is adapted

- to engage in the coaxial groove 29 formed in the opening 23 in proximity to the outer extremity thereof, as a means of holding the cigarette holder proper 24 in the opening 23 formed in the body member 10. It should be understood that the cigarette holder proper 24 is urged outwardly, so as to frictionally engage the body member 10. The enlarged head 16 of the ejector 15 is provided with extended portions 30 and 31 positioned approximately opposite each other, and of suitable size to engage in the slots 27 formed in the cigarette holder proper 24.
- 15 The above described construction is such as will permit a cigarette 32 to be securely engaged by the cigarette holder proper, as clearly shown in Fig. 4 and which will permit the said cigarette, when smoked or the 20 stub of the cigarette 32 to be ejected from my improved cigarette holder, when the stem 15 is forced inwardly, as above set forth. It should be further understood that the extended portions 30 and 31 of the 25 ejector 15 may be engaged in the slots 27 formed in the cigarette holder proper 24 and the said cigarette holder proper partially rotated, as a means of more readily ejecting the said cigarette stub.
- 30 While the invention has been described as used as a cigarette holder, it is to be understood that I reserve the privilege of using my invention also as a cigar holder.
- Having thus described my invention, what 35 I claim as new and desire to protect by Letters Patent of the United States is as follows:
1. In a cigarette holder of the class described, a cigarette holder proper adapted to frictionally engage in a tapered axial opening formed in a cigarette holder, a snap ring, adapted to engage in a coaxial groove

formed in the said opening, as a means of holding the said cigarette holder proper in place.

2. In a cigarette holder of the class described, a cigarette holder proper adapted to frictionally engage in a tapered axial opening formed in a cigarette holder, a snap ring adapted to engage in a coaxial groove 50 formed in the said opening, as a means of holding the said cigarette holder proper in place, an ejector slidably mounted in the said cigarette holder, a stem removably secured to the said ejector.

3. In a cigarette holder of the class described, a cigarette holder proper adapted to frictionally engage in a tapered axial opening formed in a cigarette holder, a snap ring, adapted to engage in a coaxial groove 60 formed in the said opening, as a means of holding the said cigarette holder proper in place, an ejector slidably mounted in the said cigarette holder, a stem removably secured to the said ejector, said ejector provided with extended portions adapted to engage in elongated slots formed in the said cigarette holder proper, as a means of partially rotating the said cigarette holder proper.

4. A cigarette holder of the class described, comprising a cigarette holder body having a tapered axial opening provided with a coaxial groove, ejector means associated with said body, a cigarette holder 75 proper formed with a longitudinal slot, frictionally engaged in the tapered axial opening, and a ring formed with a slot and engaged in the coaxial groove, and holding the cigarette holder proper in place.

In testimony whereof I have affixed my signature.

ADOLPH RAIMUND BAUMANN.
